UNITED STATES PATENT OFFICE.

JAY E. TONE, OF DES MOINES, IOWA, ASSIGNEE TO TONE BROTHERS, OF DES MOINES, IOWA, A CORPORATION OF IOWA.

PERCOLATOR.

1,319,661.

Specification of Letters Patent. Patented Oct. 21, 1919.

Application filed August 16, 1915. Serial No. 45,826.

To all whom it may concern:

Be it known that I, JAY E. TONE, a citizen of the United States, and resident of Des Moines, in the county of Polk and State 5 of Iowa, have invented a certain new and useful Percolator, of which the following is a specification.

The object of my invention is to provide a percolator of simple, durable and inexpensive construction for the purpose of removing the flavoring extract from material such, for instance, as vanilla beans.

A further object is to provide means whereby a continuous circulation may be established through a percolating means 15 while the contents thereof are under a high pressure.

A further object is to provide means for maintaining the liquid which is being 20 flavored at a relatively high temperature.

A further object is to provide a device adapted to bring the material with which the liquid is being flavored into contact with the largest practicable amount of such liquid.

25 My invention consists in the construction, arrangement and combination with a percolator receptacle of common construction and a means for mechanically forcing liquids slowly through the percolator from top to bottom during the time that the liquids are being subjected to heat, and also for automatically regulating the temperature of the liquid in the receptacle, whereby the objects contemplated are attained, as 30 hereinafter more fully set forth, pointed out in my claim, and illustrated in the accompanying drawings, in which:

The device is illustrated in side elevation, the main receptacle and other parts being 40 shown in section to illustrate the interior construction.

Referring to the accompanying drawings, I have used the reference numeral 10 to indicate the main receptacle provided at its 45 upper end with the detachable cover 11, held in place by adjustable clamping devices 12. The cover 11 and clamping devices 12 are of such strength and so arranged that a liquid tight joint may be maintained 50 although the interior of the receptacle 10 be under high pressure. On this cover I preferably provide a safety valve 13. Beneath the bottom of the receptacle 10 is a

steam jacket 14 having a drainage pet-cock 15. 55

Within the interior of the main receptacle is a bag 16 made of a material that will permit the circulation of liquid through it and will retain such material as, for instance, ground vanilla beans. This bag is 60 made detachable by being provided with one or more metal rings 17, the upper ones of which rest upon the lugs 18, and the lower ones being formed from resilient metal whereby they may be compressed sufficiently 65 to pass the lugs 18 when the bag is being removed or installed. The bag 16 is of such depth as to fill from a third to a half of the interior of the receptacle 10.

Communicating with the upper portion of 70 the receptacle 10 is a horizontal circulating pipe 19, and communicating with the bottom of the receptacle and extending through the steam jacket 14, is a vertically arranged circulating pipe 20. This latter has a valve 21 75 at its lower end through which the contents of the receptacle may be drawn off when desired.

Communicating with the pipe 20 is a horizontally arranged circulating pipe 22 80 and between the pipes 22 and 19 is a vertically arranged circulating pipe 23. At the juncture of the pipes 22 and 23 I provide a rotary pump 24 of any ordinary construction. It is thought to be unnecessary 85 to illustrate and describe the pump herein in detail. The pump may be driven by means of the pulley 25 and belt 26 or in any other suitable manner.

I preferably arrange near the central 90 portion of the circulating pipe 23 a section of glass pipe 27 through which the movement of the liquid may be conveniently observed.

In order to automatically regulate the 95 temperature of the contents of the receptacle, I preferably provide on the steam pipe 28 that leads to the steam jacket 14 a valve 29. This valve is controlled by a thermostatic device comprising a closed tube 30 100 inserted in the upper end of the pipe 23 and having its interior in communication with a small pipe 31, which pipe leads to the tube 32 and contains the thermostatic device of ordinary construction by which the valve 105 29 is closed when the temperature of the

liquid contained within the device reaches the point where the said liquid is expanded to a certain predetermined degree and this contraction and expansion of the liquid 5 causes the valve to be opened or closed.

The particular construction of this thermostatic device forms no part of my present invention and for that reason it is unnecessary to fully illustrate and describe it, as 10 any ordinary themostatic device may be employed in its stead. The numeral 33 indicates a thermometer arranged adjacent to the pipe 19, so that the temperature of the liquid passing through the pipe may be determined at a glance by the operator. 15

In practical operation the bag 16 is partially filled with the material from which the flavoring is to be extracted. I have used this device successfully for the extraction of 20 the flavoring from vanilla beans, although I do not intend to be understood as limiting my invention to the use of any particular kind of material. After the material has been deposited in the bag, the receptacle 10 is filled with liquid to a point above the pipe 19, and the cover clamped in place. Then steam is admitted to the steam jacket 25 to heat the liquid and the rotary pump is then operated. The operation of the pump preferably continues during the entire process of extracting the flavoring from the material. The result of the operation of this 30 rotary pump is that the liquid is drawn slowly through the mass of material being operated on, and from the bag downwardly and then through the pump and is returned 35 to the top of the bag. If it should occur that

any solid materials should enter the space between the bottom of the bag and the bottom of the receptacle, then such materials 40 will be forced upwardly through the pump and circulating pipes and be again discharged in the top of the bag, so that after the process has continued for the proper length of time the liquid below the bag is 45 relatively clear and free from all solid substances, and any impurities of any kind that may have been developed during the process of percolation have been returned and deposited on top of the mass of material with- 50 in the bag. The operator may at all times clearly see the condition of the liquid through the glass section 27 of the circulating pipe. 55

I claim as my invention:

In a percolator, a substantially cylindrical container for liquid having a plurality of inwardly projecting spaced lugs on its inner surface disposed in the same horizontal plane, and a substantially cylindrical receptacle of pliable porous material adapted to be received within said container and having resilient distending wings at its upper and lower ends, of substantially the same diameter as the interior of the container, whereby the lower ring may be distorted to enable it to be forced past said lugs and the upper ring may rest on said lugs to thereby support the receptacle. 60 65

Des Moines, Iowa, June 29, 1915.
